UNITED STATES PATENT OFFICE.

SEVER P. KILLY, OF RHAME, NORTH DAKOTA.

DOLL-HEAD.

1,255,889.

Specification of Letters Patent. Patented Feb. 12, 1918.

Application filed September 22, 1917. Serial No. 192,718.

To all whom it may concern:

Be it known that I, SEVER P. KILLY, a citizen of the United States, residing at Rhame, in the county of Bowman and State 5 of North Dakota, have invented new and useful Improvements in Doll-Heads, of which the following is a specification.

This invention relates to a head which is primarily intended for a doll, although the 10 construction of the head is such that it may be used in connection with other manikins when found desirable.

The primary object of the invention is to provide a head of this character wherein the 15 eye balls are so mounted and connected with operating mechanism therefor that when the doll to which the head is attached is held in a reclining position and rocked, the eyes will gradually close and remain closed until 20 the doll is moved to an upright position, at which time the eyes will open.

With these and other objects in view, the invention resides in the novel combination and arrangement of parts, which will be 25 hereinafter described and particularly pointed out in the claims.

The preferred embodiment of the invention has been illustrated in the accompanying 30 drawing, although no restriction is necessarily made to the precise details of construction therein shown, as changes, alterations, and modifications within the scope of the claims may be resorted to when desired.

35 In the drawings:—

Figure 1 is a vertical longitudinal section through a doll head constructed in accordance with the invention, the head being shown in position wherein the eyes appear 40 open.

Fig. 2 is a view similar to Fig. 1 wherein the head is shown in a reclining position with the eyes closed.

Fig. 3 is a vertical transverse section on 45 the line 3—3 of Fig. 1.

Like characters of reference denote corresponding parts throughout the several views in the drawing.

Referring now to the drawing in detail, 50 the letter A designates a doll head constructed in accordance with the invention and formed from any material suitable for the purpose, such as clay, or the like with the head having formed therein a pair of spaced openings 5.

Mounted within the head A are a pair of

spaced bearings 6 in which is mounted to turn in the rear of the openings 5 a transversely extending shaft 7. The shaft 7 has mounted thereon in line with the openings 60 5 spaced balls 8 having painted thereon a representation of the pupils and lids of the human eye, so that the balls 8 serve as the eye balls of the head A. The shaft 6 is yieldably held against rotation in one direction by a spring 9, one terminal of which is engaged with the shaft 7 and the other end of the spring with one of the bearings 6, whereby the spring may also be employed to restore the shaft 7 to its normal position 70 when released from engagement with the operating mechanism therefor which will now be described.

A shaft holder 10 is pivotally mounted in the head A below the shaft 7 and has mounted to turn therein a shaft 11, at one end of which is a worm 12 to mesh when the head 75 A is in a reclining position with the teeth on a gear wheel 13 fixed to the shaft 7 between the balls 8.

A weighted yoke 14 has the arms thereof 80 swingingly connected with the shaft 11 adjacent its other end and serves when the head A is in a reclining position to maintain the worm 12 in engagement with the wheel 85 13 and upon movement of the head to an upright position swings the shaft 11 to a position in which the worm 12 is out of engagement with the gear wheel 13.

One of the arms 15 of the yoke has secured 90 thereto a leaf spring 16, which through its engagement with a ratchet wheel 17 on the shaft 11 serves as a pawl to rotate the shaft 11 as the yoke is swung backwardly and forwardly on the shaft 11 when the doll is 95 in a reclining position and rocked.

One of the bearings 6 is provided with spaced stop lugs 18 and 19, with the stop lug 18 so arranged with relation to an arm 20 on the shaft 7 that when the actuating 100 mechanism for the shaft 7 is released therefrom the arm 20 through its engagement with the said stop lugs will prevent the likeness of the pupil of the human eye from being carried out of alignment with the eye 105 openings in the head. The stop lug 19 is so arranged with relation to the arm 20 that when the likeness of the pupil of the human eye on the ball 8 has been moved out of alignment with the eye openings in the head 110 A by the operating mechanism for the shaft 7, the arm 20 will engage with the stop lugs

to prevent the balls from being turned by the operating mechanism to a position in which the likeness of the pupil of the human eye will again be in registration with the eye opening.

From the foregoing description taken in connection with the accompanying drawing it is at once apparent that the doll head has been provided with eyes and operating mechanism therefor which is so constructed, that when the head is held in a reclining position and rocked the eyes will gradually close and remain closed until the head is again moved to an upright position, at which time the eye will automatically open.

Having thus described the invention, what is claimed as new, is:—

1. A doll head having eye openings therein, a shaft yieldably held against turning movement within said head, eye balls fixed to said shaft in line with said eye openings, a shaft mounted to tilt in said head and engage with the first-mentioned shaft when

said head is in a reclining position, and a weight swingingly connected with the second-mentioned shaft and operable to rotate the same when said head is rocked.

2. A doll head having eye openings therein, a shaft within said head, a spring engaged with said shaft and yieldably holding the same against turning movement in one direction, eye balls on said shaft in line with said eye openings, a gear wheel on said shaft between said eye balls, a pivoted shaft holder within said head, a second shaft rotatably mounted in said holder, a worm adjacent one end of the second-mentioned shaft to engage said wheel when the head is in a reclining position, a weighted yoke swingingly connected with the second-mentioned shaft adjacent its opposite end, a ratchet wheel on the second-mentioned shaft adjacent said yoke, and a pawl on said yoke to engage said ratchet wheel.

In testimony whereof I affix my signature.

SEVER P. KILLY.
